FOLDING TABLE

Floyd H. Hatfield, Rawlins, Wyo.

Application May 6, 1933, Serial No. 669,719½

2 Claims. (Cl. 45—116)

These improvements are on my former application, Serial No. 546,543 series of 1925, applied for June 24, 1931, now Patent No. 1,905,282 of April 25, 1933.

5 This invention relates to a folding table adaptable for various purposes and which will be compact when folded to permit convenient storing in a small space and will be easy to carry from one place to another and has for the primary object, 10 the provision of a collapsible top and folding legs so arranged that the legs will automatically assume supporting position when the top is extended and will fold within the top when the latter is collapsed, thereby providing a table requiring only minimum effort on the part of a 15 person to extend for use or to collapse for storage. Another object of this invention is the provision of operating means for the legs, and the provision of operating means for locking the legs 20 in extended position, effected by the movements of the top for folding or extending the legs in accordance with the collapsing and extending of the top and which will effectively brace and hold the legs in supporting position against accidental 25 folding when the table is in use.

A further object of this invention is the provision of a folding table of the above stated character which will be simple, durable and efficient and which may be manufactured and sold at a 30 comparatively low cost.

With these and other objects in view, this invention consists in certain novel features of construction, combination and arrangement of parts to be hereinafter more fully described and 35 claimed.

For a complete understanding of my invention, reference is had to the following description and accompanying drawings, in which

Figure 1 is a bottom plan view illustrating the 40 operating means between the table top and the legs, and illustrating the operating means between the extending of the legs and the locking device for the legs in extended position.

Figure 2 is a fragmentary side sectional view 45 taken on the line x—x of Figure 1.

Figure 3 is a fragmentary bottom plan view illustrating the operating means between table top and the legs in folded position, and illustrating the operating means between the folding of the 50 legs and the unlocking device.

Figure 4 is an isometric view of a pivot table (11) and a stop (29).

Figure 5 is a typical half section of leg (3), showing how the round (4) is attached to the 55 leg, and also how the brace (10) is attached in-

side the leg, and illustrating the recessed portion of the leg which partially encases the brace (10) when the leg is in folded position.

Figure 6 is an isometric view of the angle channel guide (5). 60

Figure 7 is an isometric view of an anchor post (20).

Figure 8 is an isometric view of an anchor post (21).

Figure 9 is an isometric view of a leg brace (10) 65 with suitable head (32).

Figure 10 is an isometric view of a quarter round sliding mechanism (7) showing an anchor post (24), a slotted guide (25), and a lever engager (27). 70

Figure 11 is an isometric view of a quarter round sliding mechanism (6) showing an anchor post (24), a slotted guide (26), and a lever engager (28).

Figure 12 is an isometric view of a leg brace 75 guide track (8) showing the lock lever slots (30) and a leg brace head stop (31).

Figure 13 is an isometric view of a round (4) showing how a dowel post (9) is arranged.

Referring in detail to the drawings, the number 22 indicates the tops of the two sections of the table being suitably secured to the side and end members 1 and 23 respectively. The inner side members are connected by hinges 17 on which the two sections may be swung to and 85 from each other for the purpose of collapsing or extending the table top. The outer side members are equipped with hand grips 2 for carrying purposes, and all four side members are circularly recessed near the inside ends to receive 90 the small ends of the round 4.

When the table is extended, the outer surfaces of the inner side pieces 1 come into an abutment engagement and provide a continuous supporting surface for the table. When collapsed, the bottom surfaces of the end members 23 come into abutting engagement with the bottom surfaces of opposite end members 23, and the bottom surfaces of the outer side members 1 come into abutting engagement, and the bottom 95 surfaces of the inner side members 1 come into abutting engagement, providing a compact unit.

To the inside surface of the end members 23 and the top 22 in the location illustrated in Figure 1 are attached suitably the angle channel guides 5. The rounds 4 with legs 3 attached as shown in Figure 5 are placed in parallel position with the end members 23, with the small ends of the rounds 4 set into the rounded recesses provided for them near the ends of the side mem- 105
110

bers 1. The legs 3 and the dowel posts 9 are located on and in the round 4 as indicated in Figure 5 and Figure 13, the legs and the dowel posts 9 in a vertical position or right angles to the top 22, in the locations indicated on the rounds 4 in Figure 1 when the legs are extended.

The pins of the quarter round sliding mechanisms 6 and 7 are engaged in channels of the angle channel guide 5 in such a manner that the 10 dowel post 9 engages with the slotted guides 26 and 25, with respect to the positions as shown in Figure 1, and with the lever stops 28 and 27 nearest the inner surface of the top 22 and the 15 anchor posts 24 near the ends of quarter round mechanisms 6 and 7 most adjacent to the inner side members 1.

To the inner surface of the top 22 are suitably attached with the bracket 15 and other means the leg brace guide tracks 8 parallel with the side 20 members 1 and located as shown in Figure 1 with the slots 30 most adjacent to the end members 23. The leg brace guide tracks 8 slidably receive the heads 32 of the leg braces 10.

To the inner surface of the top 22 and located 25 as shown in Figure 1 are suitably attached the pivot tables 11 with the stops 29 located in the general direction of the table's corners.

On the pivot table's poles 11 are placed the 30 lever arms 12 and in turn to the lever arms 12 are freely attached for swivel action the locking arms 13 and 14 with respect to their respective positions as shown in Figure 1 with their shortest sides most adjacent to the end members 23. The locking arms 13 and 14 are inserted in the 35 guide brackets 16 suitably attached to top 22 which insure the locking arms 13 and 14 entering the slots 30 in the leg brace guide tracks 8.

To the inner surfaces of the inner side members 1 are suitably attached the anchor posts 20 40 and 21 with regard to their positions as shown in Figure 1. Between these anchor posts 20 and 21 and the anchor posts 24 are freely attached the arms 19 and 18 with regard to their positions as shown in Figure 1.

When it is desired to place the table in use, the two sections of the table are swung apart in the act of extending the table, from a collapsed manner as indicated in Figure 3, the anchor posts 20 and 21 are caused to pull on the arms 19 and 18, by reason of their proximity to the seat of the 50 whole action. The pull on the arms 19 and 18 is in turn transmitted to the quarter round sliding mechanisms 6 and 7 through the anchor posts 24. This pull in the direction of the inner side members 1 causes the quarter round sliding mechanisms 6 and 7 to slide in the angle channel guide 5 causing the slotted guides 26 and 25 to force the dowel pin 9 to ride in the direction of the 55 slots 26 and 25. The dowel pins 9 in riding in the slotted guides 26 and 25 rise from a position parallel to the tops 22 to a position at right angles to the top 22. As the action of the dowel pin 9 and the leg 3 are concurrent in action on the round 4, the leg 3 comes to a right angle position to the top 22 or that of being extended. As the 60 leg 3 rises the brace 10 moves slidably by means of its head 32 in the leg brace guide track 8 to a stopped position against the stop 31 in the brace guide track 8.

As the quarter round sliding mechanisms 6 and 7 move in the general direction of the inner side members the lever engagers 28 and 27 engage with the free end of the lever arms 12 which pivot on the pivot pole of pivot table 11, causing the locking arms 14 and 13 to be thrust by reason of a swivel action through the guides 16 and into the slots 30 of the leg brace guide tracks 8, locking the head 32 of the leg brace 10 between the stops 31 and the ends of the said locking levers 14 and 13.

The collapsing of the table is exact reverse process with legs 3 assuming the position as shown in Figure 3, partially encasing the leg braces 10 which have in the reverse action been freed by the locking arms 14 and 13, allowing the heads 32 to slide towards the opening end of leg brace guide track 8.

As the quarter round sliding mechanisms 6 and 7 return in the general direction of the outmost side members 1 the free ends of lever arms become disengaged with the receding lever engagers 28 and 27. The free ends of lever arms 12 are carried by the quarter round sliding mechanism to a stopped position against the stop 29, preventing the lever arm 12 from turning too far so as not to fail engagement with the lever engagers 28 and 27. As the lever arms 12 move to this stopped position against stop 29, they activate the locking arms 14 and 13 to withdraw from the slots 30 and to free the heads 32 of the leg brace 10.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A folding table comprising a folding sectional top, legs pivoted to the sections of said top, 115 leg brace arms attached to legs, heads of brace arms slidably in guides attached to sections of top, port holes in said brace arm guides, locking levers pivoted to sections of top, so situated as to become engaged with lever engager slots in 120 quarter round sliding mechanism, thus causing locking levers to enter port holes of leg brace arm guides or to be pulled from port holes of leg brace arm guides, thereby, automatically locking or unlocking said leg brace arms by folding 125 or unfolding sectional top.

2. A folding table comprising a sectional top, said sections having folding relation, legs attached to rounds with dowel ports pivoted to the sections of top, quarter round sliding mechanism 130 seating over rounds and sliding in angle channel guides attached to sections of top, said dowel ports extending through slotted guides in quarter round sliding mechanism, said quarter round sliding mechanism attached by arms to opposite sections 135 of top by means of arm posts, thereby causing the legs to move into folding position when sections of the top are folded and to move the legs into supporting position when the sections of the top are unfolded.

FLOYD H. HATFIELD.
